UNITED STATES PATENT OFFICE.

SABELLA GERTRUDE DOHERTY, OF NEW YORK, N. Y.

DESIGN FOR AN EASEL.

SPECIFICATION forming part of Design No. 36,644, dated November 24, 1903.

Application filed October 26, 1903. Serial No. 178,642. Term of patent 14 years.

To all whom it may concern:

Be it known that I, SABELLA GERTRUDE DOHERTY, a citizen of the United States, and a resident of the city of New York, borough 5 of Manhattan, in the county and State of New York, have invented a new, original, and ornamental Design for an Easel, reference being had to the drawing, in which the figure is a perspective view of an easel, showing my 10 ornamental design.

I claim as new and desire to secure by Letters Patent—

The ornamental design for an easel, substantially as herein illustrated.

In testimony whereof I have signed my 15 name to this specification in the presence of two subscribing witnesses.

SABELLA GERTRUDE DOHERTY.
